SURFACE CONDENSER

Filed Dec. 9, 1927

FIG. 1.

FIG. 2.

INVENTOR.
John F. Kirgan.
BY *Robert Olden*
HIS ATTORNEY

UNITED STATES PATENT OFFICE.

JOHN F. KIRGAN, OF EASTON, PENNSYLVANIA, ASSIGNOR TO INGERSOLL-RAND COMPANY, OF JERSEY CITY, NEW JERSEY, A CORPORATION OF NEW JERSEY.

SURFACE CONDENSER.

Application filed December 9, 1927. Serial No. 238,866.

This invention relates to steam condensers of the surface type and more particularly to that type in which the steam is adapted to flow radially into a tube nest toward a centrally disposed air outlet.

It is an object of this invention to cause the steam to be condensed to flow in greater quantities toward the cooler portion of the tube nest in order to utilize the tube condensing surface most efficiently in a radial flow type of condenser.

Other objects and advantages of the invention will be in part obvious and in part pointed out hereinafter.

15 In the drawing in which similar reference characters refer to similar parts,

Figure 1 is a vertical longitudinal section of a condenser constructed in accordance with the practice of the invention, and

20 Figure 2 is a cross section of the condenser taken along the line 2—2 of Figure 1 looking in the direction of the arrows.

Referring to the drawing, the condenser comprises a casing A preferably of cylindrical form as shown in Figure 2 within which is arranged a nest of tubes B spaced from the inner walls of the casing A. The casing A is provided with a steam inlet C and an outlet D for condensate. At its entrance the 25 casing A is furnished with an inlet circulating water box E for supplying water to the tubes B and a discharge water box F at the end of the casing opposite to the inlet water box E into which the tubes B discharge the 30 used water. The tubes B are sealed in tube sheets G to prevent leakage of the circulating water from the water boxes E and F to the 35 interior of the casing A.

The nest of tubes B is spaced from the 40 side walls of the casing A to permit steam to enter the tube nest radially from all sides.

The condenser thus constructed is known as a radial flow type since the steam is adapted to enter the tube bank from all sides and flow 45 toward centrally disposed air evacuating apparatus by means of which the vacuum within the condenser is maintained. To this end there is provided a devaporizer or cooler comprising a shell H preferably cylindrical in 50 form and extending continuously the length of the casing A being supported at its ends by suitable brackets J mounted on the tube sheets G. The shell H is provided with perforations K and is in this instance cylindrical to house 55 cooling and devaporizing tubes L arranged in

a generally cylindrical nest formation surrounding an axially disposed air withdrawal pipe O. If desired, the pipe O may be in two parts joined at the end by means of a block P, each part being perforated as at Q to permit the air and uncondensable vapors to enter. The pipe O communicates with the exterior of the casing through conduits R formed in the water boxes E and F and are connected to suitable vacuum producing apparatus such as steam jets S. In the general operation of the condenser the vacuum produced in the air withdrawal pipe O draws the steam into the inlet C and from all sides through the nest of tubes B to be condensed. The air and non-condensable vapors are drawn through the perforations K of the shell H into the interior of the shell where the air is devaporized by passing around the cooling tubes L and thence through the perforations Q into the pipe O. The water of condensation is withdrawn by suitable pump (not shown) at the condensate outlet D.

It is the natural tendency of the steam to penetrate the nest of tubes B more deeply in 80 the warmer portions of that nest. At the cooler portions of the tube nest nearer the water inlet box E the steam is normally completely condensed at less depth of penetration. To counteract this tendency the perforations 85 K in the casing H are made of greater size adjacent the cooler portions of the tube nest and decrease in size in the direction of the discharge water box F and the warmer portions of the tube nest. By means of the 90 graduated size of the perforations or apertures K the resistance to the steam flowing through the tube nest is least adjacent the inlet water box E and increases in the direction of the discharge water box F. By this 95 means equal depth of penetration into the tube nest by the steam is secured. The advantage of this arrangement is that the coldest portions of the tubes B are caused to condense the most steam which is admitted there- 100 to by the larger perforations and furthermore, all of the tube surface is used for condensing steam.

Thus by the above construction are accomplished among others; the objects hereinbefore referred to.

I claim:

1. In a surface condenser, a casing having a steam inlet and an outlet for condensate, a tube nest arranged within the casing to 110.

permit steam to enter the nest from all sides, and air conveying means centrally disposed in said tube nest and adapted to create greater resistance to steam flow at certain portions of the tube nest than at other portions.

2. A surface condenser comprising a casing, a tube nest arranged within said casing to allow steam to enter radially into said nest from all sides, a devaporizer section axially disposed within said tube nest and having entrance orifices of greater size adjacent certain portions of said tube nest than at other portions.

3. A surface condenser comprising a casing, a tube nest arranged within said casing to allow the entrance of steam into said nest radially from all sides, a devaporizer section centrally and axially disposed in said tube nest comprising a shell having orifices of greater size adjacent the cooler portions of said tube nest, cooling tubes within said devaporizer and an air removal pipe disposed axially and centrally among said cooling tubes

and provided with perforations along its length.

4. A steam condenser comprising a substantially cylindrical shell having an inlet for steam and an outlet for condensate, inlet and discharge water boxes at opposite ends of the shell, a nest of circulating water tubes in the shell and spaced from the sides of said shell to permit entrance of steam radially into the nest of said tubes from all sides, a devaporizing section arranged within said nest of circulating water tubes comprising a shell extending continuously the length of said casing and having perforations decreasing in size in the direction of the said discharge water boxes, cooling and devaporizing tubes within said shell in nest form and a perforated air withdrawal pipe arranged centrally in said nest of cooling and devaporizing tubes.

In testimony whereof I have signed this specification.

JOHN F. KIRGAN.
